UNITED STATES PATENT OFFICE.

CHARLES H. DEMPEWOLF, OF OSWEGO, NEW YORK.

COMBINED TUMBLER, TOOTHBRUSH, AND TUBE-PASTE HOLDER.

1,407,347.

Specification of Letters Patent. Patented Feb. 21, 1922.

Application filed September 19, 1921. Serial No. 501,593.

To all whom it may concern:

Be it known that I, CHARLES H. DEMPEWOLF, a citizen of the United States, residing at Oswego, in the county of Oswego and

5 State of New York, have invented certain new and useful Improvements in Combined Tumbler, Toothbrush, and Tube-Paste Holders, of which the following is a specification.

This invention relates to holders for toilet 10 articles, and the primary object of the invention is to provide a novel device for holding

a tumbler, a plurality of tooth brushes or the like, and a tube of tooth paste, the parts of the device being so constructed as 15 to form a unitary article, and to hold the tumbler in such a manner as to preclude accidental displacement thereof, and to permit the same to form a cover for the tooth brushes.

20 Another object of the invention is to provide a combined holder of the above character, embodying a body for supporting the tumbler and the tooth brushes having supporting legs or brackets stamped therefrom, 25 whereby the body may be readily secured in position on a suitable support.

A still further object of the invention is to provide a combined holder for toilet articles, which will be durable and efficient in 30 use, one that will be simple and easy to manufacture, and one which can be placed upon the market at a minimum cost.

With these and other objects in view, the invention consists in the novel construction, 35 arrangement and formation of parts, as will be hereinafter more specifically described, claimed and illustrated in the accompanying drawings, forming a part of this specification, in which drawings:

40 Figure 1 is a side elevation of the improved combined toilet article holder.

Figure 2 is a longitudinal section through the holder taken on the line 2—2 of Figure 1.

Figure 3 is a vertical longitudinal section 45 through the holder, taken on the line 3—3 of Figure 2.

Referring to the drawings in detail, wherein similar reference characters designate corresponding parts throughout the 50 several views, the letter A generally indicates the improved holder, which includes the body 5, preferably stamped or otherwise formed from a single blank of sheet metal, which may be plated so as to present a pleasing

55 appearance to the eye.

The body 5 includes the annular upstand-

ing ring 6 and an inwardly extending annular supporting flange 7. This flange 7 may be provided at spaced points with inwardly extending key hole slots 8, which serves as 60 means for holding tooth brushes indicated by the reference character B. The inwardly extending flange 7 forms a support for a glass tumbler C, and the annular rim 6 provides means for preventing the accidental displacement of the tumbler from off of said flange. 65

It can be seen that the tumbler B is placed in an inverted position on the flange 7, thus forming a complete cover or housing for 70 the tooth brushes B, preventing foreign matter from getting upon the bristles thereof. This also prevents the entrance of foreign matter into the tumbler.

If found undesirable, the free edge of 75 the rim 6 may be rolled outwardly to provide a bead 10, which acts to strengthen the body and to eliminate the presenting of a sharp edge.

The rim 6 has struck out from the same, 80 supporting arms or brackets 11, which are extended outwardly in parallel relation to each other from the rim. The free ends of the arms or brackets 11 may be bent outwardly in opposite directions to provide at 85 attaching feet 12, which may receive a suitable fastening element 13, whereby the holder may be secured to a suitable support. As shown, the striking out of the arms or brackets 11 form slots 14 in the rim, which 90 serve to lighten the weight of the body of the holder. The upper edges of the arms or brackets 11 are notched as at 15, and serve to form a holder for a tube of tooth paste or the like D, as clearly shown in 95 Figure 1 of the drawings.

It can be seen that the brushes B can be removed from the holder when desired, without the removing of the tumbler C, as the brushes can be easily slipped through the 100 bottom of the holder. It is to be also noted that the slots or openings 8 form means for permitting the water from the tumblers to readily drain off of the body of the holder, thus keeping the holder in a clean and 105 sanitary condition.

From the foregoing description, it can be seen that an exceptionally simple and durable article has been provided, which will effectively support a plurality of tooth 110 brushes, a tumbler which will act as a cover for the brushes, and a tube of tooth paste.

Changes in details may be made without departing from the spirit or scope of this invention; but,

I claim:

- 5 1. A toilet article holder comprising an open body including an annular tumbler supporting flange and an annular right angularly disposed tumbler guard flange, the supporting flange having a plurality of 10 tooth brush receiving slots formed therein extending inwardly from the inner edge of the supporting flange and terminating adjacent to the guard flange and forming drain openings for water from said tumbler, and outwardly extending supporting arms struck out from said guard flange.
- 15 2. A toilet article holder comprising an open body including an annular horizontally disposed supporting flange and a right angularly extending guard rim, the supporting 20

flange having a plurality of tooth brush receiving slots formed therein, outwardly extending supporting arms struck out from the opposite faces of said guard rim, the upper edges of said supporting arms having 25 tube holding notches formed therein.

3. A combined toilet holding device formed of a single blank of metal comprising an annular body including an annular horizontally disposed supporting flange having 30 a plurality of tooth brush receiving slots formed therein, and a right angularly disposed annular guard rim, outwardly extending spaced supporting arms struck from said guard rim, outwardly extending attaching 35 feet formed on said arms, the upper edges of the arms being notched for the reception of a tube of tooth paste.

CHARLES H. DEMPEWOLF.
